EDMUND KEITH, OF BUFFALO, NEW YORK, ASSIGNOR TO HIMSELF, BELA H. COLE-GROVE, AND CHAUNCEY B. HUTCHINS, OF SAME PLACE.

Letters Patent No. 94,892, dated September 14, 1869.

IMPROVEMENT IN WATER-METERS ADAPTED FOR ROTARY PUMPS.

The Schedule referred to in these Letters Patent and making part of the same.

To all whom it may concern:

Be it known that I, EDMUND KEITH, of the city of Buffalo, in the county of Erie, and State of New York, have invented a certain new and useful Improvement in Water-Meters, Pumps, Water-Wheels, Paddle-Wheels, &c.; and I do hereby declare that the following is a full and exact description thereof, reference being had to the accompanying drawings, making part of this specification.

Figure 1 is a side elevation of my improved movement, with one-half the case removed, to show the interior.

Figure 2 is a section in plane xx of fig. 1.

Figure 3 is a perspective view of one-half the case and one of the revolving wings or paddles.

Like letters of reference indicate corresponding parts in all the figures.

My improvement belongs to that class where wings or paddles, situated in a case, turn broadwise when just forward of the induction-inlet, but turn flatwise when just past the induction-outlet, to allow them to pass the butment that arrests the revolution of water.

My invention consists in imparting to the wings or paddles a constant forward revolution, by means hereafter described, instead of an alternate vibrating movement, back and forth, such as is usually produced in pumps of this kind.

In the drawings—

A indicates a case, made of halves, suitably bolted together, and provided with induction and eduction-pipes $b\ c$.

One-half of this case has formed on the inside, between the pipes, an extended flat butment, d , as clearly shown, and also around the centre, two concentric cam-ways, $f\ f'$, opposite each other, occupying respectively the segment of circles, the one being of larger diameter than the other.

Closely inside the case fits a cylindrical piston-head, B, with shaft g , by which it is operated.

This head has a central hub, h , and a concentric flange, i , which stands outside the cam-ways $f\ f'$, thus enclosing them closely, and leaving an open annular space, k , between the hub and flange.

Wings or paddles C C, filling the cross-area of the space of the case, are connected with the piston-head, so as to turn freely on their axes.

To secure this result properly, the axis l , of each, passes through flange i and enters hub h , as clearly shown in fig. 2.

This axis has two cross-arms, $m\ m'$, resting in annular space k , and coinciding in position respectively with cam-ways $f\ f'$, which they strike in their passage.

It will be seen that the butment is of such an extent that one wing does not leave it until the next

comes on, so that the open space over the top of the butment, through which the wings pass flatwise, is kept closed at all times against the unnecessary escape of water.

Before one wing leaves, the next strikes on, and the only escape of water is the small space intervening between the wings.

The wings in section are wedge-shaped, by which they fit more accurately between the butment and case in passing flatwise.

The operation will be readily understood.

As the piston-head is turned, the cross-arm m , striking the corresponding way f , causes the wing to turn broadwise across the area of the case, just past the induction-pipe b , in which position it remains till the revolution carries it just past the eduction-pipe; when arm m frees from way f , and the other arm, m' , then strikes corresponding way f' , and the wing or paddle consequently turns forward a quarter revolution flatwise, in position to pass over flat butment d .

The axial revolution of the wings is constantly forward, and never backward.

It matters not, however, which way the piston is turned, as the action is the same either way.

I am aware that in rotary pumps there are cases in which the wings turn to the right-angled position, to accomplish the same general object as above indicated, but in such cases, so far as I am aware, the wings do not have a constantly forward revolving motion on their axes, but rather an alternately vibrating forward-and-back action, first turning up to close the passage, and then turning down to open it. Such is the case in patent No. 56,627, of 1866.

The great difficulty in such cases is, that if the wings get clogged with sediment or other matter, as in breweries, for example, they cannot, by having only a partial movement, free themselves, but hold the clogging-matter and carry it around and around.

Another difficulty is, that in changing position the back motion acts against the current, and serves to check it, whereby there is loss of power, as well as effect.

The particular arrangement of the cross-arms $m\ m'$ and cam-ways $f\ f'$ are effective in producing this result, and as these parts are very simple in their construction, and are not liable to disarrangement, and being perfectly enclosed by the piston, they cannot become obstructed.

This invention is equally applicable to pumps, water-wheels, paddle-wheels for vessels, and to water-meters, by simply attaching indicatory-apparatus to the shaft.

I am aware that turning paddles, operated by cross-arms and cams, have been before known in water-wheels. Such are not the equivalent of my invention.

What I claim as my invention, and desire to secure by Letters Patent, is—

The arrangement with the case A and paddles C, of the enclosing piston-head B, with the flange *i*, enclosing the operating-parts, consisting of the cam-ways *ff'* and cross-arms *m m'*, the whole operating in the manner and for the purpose specified.

Also, the combination, with the case A and paddles C, of the flat extended butment *d*, on one side

of the case, and serving the double purpose of a stop to the water and a guide to the paddles, as described.

In witness whereof, I have hereunto signed my name, in the presence of two subscribing witnesses.

E. KEITH.
